Des. 237,034
Patented Oct. 7, 1975

237,034

CHOPSTICK ASSEMBLY

Shaun Huey, 410 Atkinson Drive, 461,
Honolulu, Hawaii 96814

Filed June 21, 1973, Ser. No. 372,299

Term of patent 14 years

Int. Cl. D7—06

U.S. Cl. D7—105

FIG. 1

FIG. 2

FIG. 5

FIG. 3

FIG. 4

FIG. 1 is a perspective view of a chopstick assembly showing my new design.

FIG. 2 is a front elevation of the chopstick assembly.

FIG. 3 is a top plan view of the chopstick assembly.

FIG. 4 is a bottom view of the chopstick assembly.

FIG. 5 is a side elevation of the chopstick assembly.

I claim:

The ornamental design for a chopstick assembly, as shown.
